UNITED STATES PATENT OFFICE.

LOLA A. BOYER, OF FIRDALE, WASHINGTON.

DESIGN FOR A SEWING-TABLE.

50,711.

Specification for Design.

Patented May 8, 1917.

Application filed January 25, 1917. Serial No. 144,540. Term of patent 14 years.

To all whom it may concern:

Be it known that I, LOLA A. BOYER, a citizen of the United States, residing at Firdale, in the county of Pacific and State of Washington, have invented a new, original, and ornamental Design for Sewing-Tables, of which the following is a specification, reference being had to the accompanying drawing, forming a part thereof.

The figure is a perspective view of a sewing table, showing my new design.

What I claim is:

The ornamental design for a sewing table, as shown.

LOLA A. BOYER.
